WILLIAM H. PAGE, OF NORWICH, CONNECTICUT, ASSIGNOR TO W. H. PAGE AND COMPANY.

Design No. 2,982, dated March 31, 1868.

DESIGN FOR A PRINTERS' BORDER.

The Schedule referred to in these Letters Patent and making part of the same.

TO ALL WHOM IT MAY CONCERN:

Be it known that I, WILLIAM H. PAGE, of the town of Norwich, in the county of New London, and State of Connecticut, have invented or produced a new and original Design of Wood Border for printing purposes, styled No. 28, for letter-press printing; and I do hereby declare that the accompanying drawing is a full and exact representation of the same.

What I claim as new, and desire to secure by Letters Patent, is—
The design for an ornamental border, as shown and described

WM. H. PAGE.
